UNITED STATES PATENT OFFICE

PETER P. SCHULTZ, OF BUFFALO, NEW YORK, ASSIGNOR OF ONE-HALF TO LOUIS GROPP, OF BUFFALO, NEW YORK

DESIGN FOR A LIGHTING FIXTURE OR THE LIKE

Application filed October 17, 1930. Serial No. 37,295. Term of patent 7 years.

To all whom it may concern:

Be it known that I, PETER P. SCHULTZ, a citizen of the United States, residing at Buffalo, in the county of Erie and State of New York, have invented a new and original Design for a Lighting Fixture or the like, of which the following is a specification, reference being had to the accompanying drawing, forming a part thereof.

The accompanying drawing shows a front elevation of my lighting fixture.

The fixture is substantially flat and of no appreciable thickness, the design characteristics being presented in the face view shown.

I claim:

The original design for a lighting fixture or the like substantially as shown and described.

PETER P. SCHULTZ.
